UNITED STATES PATENT OFFICE.

HENRY B. TEN EYCK, OF JOHNSTOWN, NEW YORK.

LACE-FASTENING.

SPECIFICATION forming part of Letters Patent No. 392,375, dated November 6, 1888.

Application filed April 7, 1888. Serial No. 269,982. (No model.)

To all whom it may concern:

Be it known that I, HENRY B. TEN EYCK, a citizen of the United States, residing at Johnstown, in the county of Fulton and State of New York, have invented certain new and useful Improvements in Lace-Fasteners; and I do hereby declare the following to be a full, clear, and exact description of the invention, such as will enable others skilled in the art to which it appertains to make and use the same.

My invention relates to fasteners for lace, cords, or strings, and is applicable to shoes, gloves, or any other article in which a lace cord or string may be employed. It consists in an improvement upon the lace-fastener set forth in my Letters Patent No. 359,477, dated March 15, 1887.

I have illustrated my invention in the accompanying drawings, and said invention is fully disclosed in the following specification and claims.

In the drawings, Figure 1 is an elevation of my improved lace-fastener. Fig. 2 is a sectional view of the same.

My improved fastener consists, primarily, of two rigid plates, A and B, each of which is provided with a bead or ridge, c, between the center and the edge of the plate projecting toward the opposing plate. The distance apart of the faces of the ridges c should be about the width of the lace employed. These plates are mounted upon the rivet D, which is preferably hollow to make the device as light as possible; but it may be a solid rivet, if desired.

At the center of each plate A B is provided a collar formed integral with the plate, which embraces the rivet D. These collars come in contact with each other and keep the plates the proper distance apart. In order to give

the rigid plate A a slight degree of elasticity, 40 I provide a cap-plate E, which is of elastic metal and extends down and over the edge of the plate A. The elastic plate E is provided with a central opening which engages the rivet, and is rigidly secured in place. 45

In the operation of the device the cord or lace to be secured is drawn between the rigid plates and passed a little more than once around the device, effecting a crossing of the lace within the ridges or beads of said plates. 50 The elasticity of the plate E allows the plate A to move slightly to accommodate itself to laces of different sizes and avoids wear. The plate also serves as a finishing for the fastener, and protects the lace and fingers from the 55 rough and rather sharp edges of the plate A.

What I claim, and desire to secure by Letters Patent, is—

1. A lace-fastener consisting of two rigid plates having an annular ridge or ridges projecting from the inner faces of the same, between the center and edges of such faces, and an elastic plate, said plates being centrally connected, substantially as described. 60

2. A lace-fastener consisting of two rigid plates having an annular ridge or ridges projecting from the inner faces of the same, between the center and edges of such faces, and an elastic plate, said plate being connected with the outer rigid plate, substantially as described. 65 70

In testimony whereof I affix my signature in presence of two witnesses.

HENRY B. TEN EYCK.
